DISTRIBUTOR BREAKER PLATE

Holland O. Woods, Ann Arbor, Mich.

Application August 18, 1949, Serial No. 111,900

10 Claims. (Cl. 200—31)

1

This invention relates to the ignition systems in use on internal combustion engines such as are used in automobiles, and more particularly to the provision of certain improvements to the existing breaker plate and breaker point assembly.

It is well known by those skilled in the art that the performance of internal combustion engines may be varied considerably by advancing or retarding the spark at any given engine speed. It is also recognized that there is a direct correlation between variations in carburetor throat pressures and the ideal time for inducing the spark in the cylinder. When the engine is being started, or is idling, carburetor throat pressures approximate atmospheric pressure, and a retarded spark is most advantageous.

Various devices are known in the art for accomplishing this retarding and advancing of the spark, which act to rotate the breaker plate in the distributor, so as to cause the fibre rubbing block on the breaker point assembly to change its position arcuately about the circumference of the rotating cam centrally located in the distributor, thereby changing the timing.

The principal objection to this type of construction is that by so varying the point of contact of the rubbing block with the cam faces, the cam angle and the spark curve are altered beyond the limits specified by the engine manufacturers, to the detriment of the performance of the engine. The breaker points may also be worn unduly.

A further objection to the rotating of the breaker plate itself, lies in the fact that the breaker plate sometimes sticks fast within the shell of the distributor casing, thereby causing the failure of the apparatus, which will result in having a constant setting of the spark, rather than a variable curve which is most desirable.

It is therefore an object of this invention to provide means for advancing and retarding the spark in an internal combustion engine including a breaker plate and associated movable interrupter which will maintain the breaker points at their specified gap throughout the entire range of the operation.

A further object is to provide a movable interrupter which will remain free for rotation relative to the breaker point assembly.

A further object is to provide a movable interrupter for use with a breaker plate in an ignition distributor, which movable interrupter may be formed to provide varying spark curves as desired.

2

Further objects and advantages of my invention will be apparent from a consideration of the following specification in connection with the appended claims and accompanying drawings in which

Fig. I is a plan view of a distributor, showing my invention, and with the cap and the distributor rotor removed,

Fig. II is a view in section on the line II—II of Fig. I, and

Fig. III is a plan view of the movable interrupter which cooperates with the breaker plate and the breaker point assembly.

In the drawings there is illustrated a distributor housing 10 having mounted thereon, by means of the plate 12 and the flange 14, any standard type of spring biased vacuum control unit 16 which is connected by the fitting 18 and the tubular member 20 to the throat of the carburetor. The vacuum control unit 16 is spring biased in a direction toward the distributor housing 10, and contains the usual diaphragm which reacts to decreases in pressure in the tube 20 to impart longitudinal movement from the housing 10 toward the fitting 18.

The breaker plate 22 is formed with a pair of upstanding ears 24 which permit its attachment to the housing 10 by the screws or rivets 26, thereby securing the breaker plate 22 against rotative movement relative to the housing 10. The condenser 28 is mounted on the plate 22 by means of a ground clip 30 and the screw 32, and has the usual electrical conductor 34 employed in the ordinary manner.

The breaker plate 22 is fitted with an aperture 36 positioned relatively closely to the housing 10, for a purpose as will appear later. It is likewise fitted with the eccentric device 38, formed with a screw-head slot 40, and with a tap screw hole positioned to receive the clamping screw 42.

Centrally disposed with respect to the circular plate 22 is the upstanding bearing boss flange 44, formed with an annular shoulder 46 to position the same with respect to the plane of the breaker plate 22. The bearing 44 is likewise formed with an opening 50 which extends almost down to the shoulder 46, for a purpose as will appear later. Centrally disposed with respect to the housing 10, as well as the plate 22 and the bearing 44, is the rotating shaft 52 which has at its upper end 54 an aperture 56 and a slot 58 to receive and position the rotor, not shown.

Mounted on the rotating shaft 52 for rotation therewith is the timer cam 60 having a number

of lands 62 and high points or faces 64. It will be appreciated that I have illustrated in Fig. I a cam 60 having 8 high points or faces 64, which is adaptable only for use with an 8-cylinder engine. The number of cylinders in the engine and the corresponding number of lands and faces on the timer cam 60 has nothing to do with my invention.

Pivottally mounted on the pivot pin 66 is the usual breaker point assembly 68 which is held in position on the breaker plate 22 by engagement of the clamping screw 42 through the slot 70 and is positioned by use of the eccentric 38 prior to the tightening of the clamping screw 42. The breaker point assembly 68 has an extension 72 and an upturned ear 74 which supports the fixed breaker point 76. It likewise has an apertured lug 78 which carried the electrical connection 80 which functions in the usual manner in combination with the condenser 28.

The movable contact 82 is mounted on the end of the arm 84 which in turn is mounted for pivotal movement about the pivot pin 66 through the insulating block 86. Attached to the arm 84 as by the rivet 88 is the conducting spring 90, which amounts to an extension of the contact arm 84, and extends back around the pivot post 66 and over to the apertured lug 80. The conducting spring 90 urges the rubbing block 92 toward the timer cam 60, and the contact arm 84 therefore responds to movement of the rubbing block 92 as it would alternately engage the lands 62 and the faces 64 of the cam 60, and thereby moves the contact point 82 into and out of engagement with the contact point 76.

Most of the structure described thus far can be found in many distributors in wide use, and the parts described are not varied in their function or utilization in connection with my invention.

As shown particularly in Fig. 3, I have provided the movable interrupter 94 formed with a lower shoulder 96 and an upstanding annular flange 98 for telescopic engagement over the bearing boss flange 44, and for rotative movement while centered thereon. The shoulder 96 is formed with a flattened portion 100 to obviate interference with the breaker point assembly 68, while the upstanding annular flange 98 is formed with an opening 102 in a position to correspond with the opening 50 in the bearing 44.

The movable interrupter 94 has fashioned on one side thereof, an extended arm 104 to which is secured an attachment fitting 106 and an axially disposed pin 108 projecting therefrom. It will be appreciated that the lower end of the pin 108 is projected into the aperture 36 for the purpose of limiting the rotative travel of the movable interrupter 94 to the two positions shown in Fig. I. Attached to the upper end of the pin 108 is the actuating arm 110 which passes through a suitable aperture not shown in the casing 10, for operative connection with the diaphragm in the vacuum control unit 16.

It will then be appreciated that under engine operating conditions such as idling in which the pressure in the tube 20 is approximately atmospheric, the spring biased vacuum control unit will urge the actuator 110 into the full line position shown in Fig. I, thereby giving a fully retarded spark to the engine. However, during normal operation at intermediate speeds the pressure in the tube 20 is considerably reduced, causing the diaphragm in the vacuum control unit 16 to overcome the spring pressure, thereby

moving the actuating arm 110 and the extended arm 104 into the dotted line position shown in Fig. I, thereby advancing the spark.

Outwardly disposed from the upstanding flange 98 is an extension arm 112 having an upstanding ear 114 to which is attached, as by the rivet 116, a resilient strip member 118 bearing a rubbing block 120 attached thereto by the rivet 122. The engaging face of the rubbing block 120 is positioned to extend through the slot 102 in the flange 98 and through the slot 50 in the bearing 44, and positioned to engage the cam timer 60 and to react therewith. The free end 124 of the resilient strip member 118 is extended for operable engagement with the rubbing block 92 on the breaker point assembly 68, and is shown, in the drawing herewith, as being an arc of a circle whose center is the axial center of the timer cam 60.

The free end 124 may be curved inwardly toward the center of the cam 60, thereby giving a smaller spark gap at the breaker points 76 and 82, under conditions when the spark is retarded than the gap which would obtain when the spark was advanced. The free end 124 may be curved outwardly with respect to the center of the cam 60, thereby giving a larger spark gap between the contact points 82 and 76 under retarded spark conditions than under conditions wherein the spark is advanced. In other words, the shape of the projecting free end 124 will determine the characteristics of the spark curve available to the engine under various conditions.

In operation, under idling conditions, the parts of the distributor will appear as shown in full line in Fig. I, thereby giving a retarded spark.

Under conditions in which it is desirable that the spark be considerably advanced, the parts will assume the position shown in dotted lines in Fig. I under the urging of the vacuum control unit 16, thereby moving the rubbing block 120 several degrees ahead, thus advancing the spark.

It will be appreciated, that, with the free end 124 of the resilient strip 118 formed as an arc of a circle centered at the center of the cam 60, the setting between the contact points 82 and 76 will be constant under all of the varying spark conditions between advanced and retarded.

Having described my invention, what I claim as new and desire to protect by Letters Patent is:

1. A distributor plate assembly for use with a distributor casing having an associated spring biased vacuum control unit, comprising a plate member adapted to be attached to said distributor casing, a breaker point assembly adjustably mounted on said plate, a rubbing block on said breaker point assembly, a centrally disposed rotatting timer cam projecting through said plate for operative engagement with said breaker point assembly, a movable interrupter centrally disposed for rotative movement about said cam, an operative connection attached to said interrupter and associated with said vacuum control unit and adapted to move said interrupter under the control of said control unit, a second rubbing block mounted on said interrupter for operative engagement with said timer cam, and means on said interrupter responsive to movement of said second rubbing block and adapted for engagement by the first rubbing block whereby said first rubbing block is moved.

2. In a distributor for engine ignition systems having a casing, a distributor plate rigidly mounted therein, a rotating timer cam centrally disposed therein and extending through said dis-

tributor plate, a breaker point assembly adjustably mounted on said plate, a rubbing block mounted on a portion of said breaker point assembly and adapted to move one of the contact points of said assembly, and a vacuum control unit operatively associated therewith, the provision of a movable interrupter member centrally disposed for rotative movement about said cam, an operative connection between said interrupter member and said vacuum control unit whereby said interrupter member is rotatively moved in response to the action of said vacuum control unit, a resilient arm attached to said interrupter member for rotative movement therewith, a second rubbing block mounted on said arm and positioned for operative engagement with said cam whereby a portion of said arm is moved radially toward and away from the center of said cam, and a curved end on said arm adjacent said second rubbing block adapted to be engaged by said first rubbing block to move the latter radially toward and away from the center of said cam.

3. A movable interrupter member adapted to retard and advance the spark for an engine and for use with a distributor having a housing, a vacuum control unit, operating means responsive to said vacuum control unit, a distributor plate attached to said housing and having a central bearing boss flange, a breaker point assembly having a fixed contact point and a movable contact point mounted on said distributor plate, a rubbing block associated with said movable contact point, and a centrally disposed rotatable timer cam, said movable interrupter member comprising a central annular guide portion for rotation upon said central bearing boss flange, an arm projecting from said guide portion and connected to said operating means and adapted to impart guided rotative movement to said guide portion, a second arm projecting from said guide portion and adapted to move therewith, a contact arm mounted on said second arm, a second rubbing block mounted on said contact arm and adapted to engage said rotatable cam, and a curved end portion on said contact arm adjacent said second rubbing block and adapted to be engaged by said first rubbing block whereby said first rubbing block is moved radially toward and away from the center of said cam in response to the movement of said second rubbing block as it engages said cam.

4. In a circuit interrupter for the spark ignition system of an internal combustion engine and incorporating supporting structure, a breaker point assembly mounted on said supporting structure in position to be actuated to intermittently make and break an electrical circuit with an attendant sparking action, said supporting structure including a bearing boss flange, the provision of a timer control member rotatably mounted about said bearing boss flange, means for adjustably moving said timer control member relative to said supporting structure and to the breaker point assembly, means in the form of a camming surface carried upon said timer control member, and means upon said breaker point assembly and engaging along said camming surface whereby the time of actuating said breaker point assembly is capable of being varied to give advanced or retarded ignition by rotating said member on said bearing boss flange and said last means point of engagement with said camming surface is changed.

5. In a circuit interrupter for the spark igni-

tion system of an internal combustion engine, said circuit interrupter incorporating supporting structure, a breaker point assembly mounted on said supporting structure in position to be actuated to intermittently make and break an electrical circuit with an attendant sparking action, and a centrally disposed rotatable cam mounted for rotative movement at least partially above the plane of said supporting structure, said supporting structure including a bearing boss flange concentric with the axis of rotation of said cam, the provision of a timer control member adapted to be rotatably mounted about said bearing boss flange in position to actuate said breaker point assembly for the contact making and breaking operations, said timer control member including a flexible arm supporting a rubbing block for operative engagement with said cam and being angularly adjustable to preselected positions for varying the time at which said breaker point assembly is actuated, and a cam surface carried on said flexible arm for actuating the said breaker point assembly.

6. In combination with a distributor plate assembly for use with a distributor casing having an associated vacuum control unit, said assembly comprising a plate member adapted to be attached to said distributor casing, a breaker point assembly adjustably mounted on said plate, a rubbing block on said breaker point assembly, a centrally disposed rotating cam projecting through said plate for operative engagement with said breaker point assembly, the provision of a movable interrupter centrally disposed for rotative movement about said cam, an operable connection attached to said interrupter and associated with said vacuum control unit and adapted to move said interrupter under the control of said control unit, a second rubbing block mounted on said interrupter for operative engagement with said cam, and means on said interrupter responsive to movement of said second rubbing block and adapted for engagement by said first rubbing block whereby said first rubbing block is moved, thereby actuating said breaker point assembly.

7. In a distributor for engine ignition systems having a casing, a distributor plate mounted therein, a rotating cam centrally disposed therein and extending through said distributor plate, a breaker point assembly adjustably mounted on said plate, a rubbing block mounted on a portion of said breaker point assembly and adapted to move one of the contact points of said assembly, and a vacuum control unit operatively associated therewith, the provision of a movable interrupter member centrally disposed for rotative movement about said cam, a central upstanding bearing member mounted on said distributor plate and adapted to locate and support said interrupter member, an operative connection between said interrupter member and said vacuum control unit whereby said interrupter member is rotatively moved in response to the action of said vacuum control unit, a resilient arm attached to said interrupter member for rotative movement therewith, a second rubbing block mounted on said arm and positioned for operative engagement with said cam whereby a portion of said arm is moved radially toward and away from the center of said cam, and a curved end on said arm adjacent said second rubbing block and adapted to be engaged by said first rubbing block to move the latter radially toward and

away from the center of said cam, whereby said breaker point assembly is actuated.

8. A movable interrupter member adapted to retard and advance the spark for an engine and for use with a distributor having a housing, a vacuum control unit, operating means responsive to said vacuum control unit, a distributor plate disposed within and attached to said housing, a centrally disposed bearing boss flange mounted on said distributor plate, a breaker point assembly mounted on said distributor plate and having a fixed contact point and a movable contact point, a rubbing block associated with said movable contact point, and a centrally disposed rotatable timer cam, said movable interrupter member comprising a central annular guide portion adapted to be mounted on said bearing boss flange for rotative movement relative thereto, an arm projecting from said guide portion and connected to said operating means and adapted to impart guided rotative movement to said guide portion, a second arm projecting from said guide portion and adapted to move therewith, a flexible contact arm mounted on said second arm, a second rubbing block mounted on said contact arm and adapted to engage said rotatable cam, and a curved end portion on said contact arm adjacent said second rubbing block and adapted to engage said first rubbing block whereby said first rubbing block is moved radially toward and away from the center of said cam in response to the movement of said second rubbing block as it engages said cam.

9. An accessory for use in an ignition distributor for an internal combustion engine, said distributor having a centrally disposed rotatable cam, bearing structure concentric with the axis of rotation of said cam, a breaker point assembly adapted to be actuated by the lobes of said cam to intermittently interrupt an electrical circuit to cause an attendant sparking action, supporting structure upon which said breaker point assembly is mounted and through which said cam projects, and means adapted to selectively impart rotary movement to said accessory within 45 said ignition distributor, said accessory com-

5 prising a movable interrupter mounted for rotative movement upon said bearing structure relative to said supporting structure said breaker point assembly and said cam, means for connecting said movable interrupter to said first means and adapted to move said interrupter with said first means, and a flexible arm on said interrupter adapted to engage said cam and respond to the camming action thereof, said flexible arm being disposed between said cam and said breaker point assembly and adapted to actuate said breaker point assembly and to vary the time at which said breaker point assembly is actuated.

10. In a distributor for engine ignition systems 15 having a casing, a centrally disposed rotatable timer cam, a breaker plate mounted within said casing and defining an aperture through which said timer cam projects, a breaker point assembly mounted on said breaker plate, a movable interrupter mounted in juxtaposition with said breaker plate for rotative movement about the axis of said timer cam, and means responsive to varying engine operating conditions and attached to said interrupter for imparting rotative 20 movement to said interrupter, the provision of a bearing boss flange centrally mounted on said breaker plate, and a guide member centrally mounted on said movable interrupter for telescopic engagement over said bearing boss flange and adapted to position and hold said movable interrupter for rotative movement about said bearing boss flange and relative to said timer cam,
